AMOS ACKLEY, OF CAMDEN, NEW JERSEY, ASSIGNEE TO AMERICAN TYPE FOUNDERS COMPANY, A CORPORATION OF NEW JERSEY

AUTOMATIC SHEET-FEEDING MECHANISM

Application filed June 9, 1928. Serial No. 284,216.

This invention relates to improvements in automatic sheet feeding mechanisms for platen pressures of the Gordon type. The object of the invention is to provide a generally improved feeder embodied in a construction of extreme simplicity.

The feeding mechanism herein disclosed is of the type known as pneumatic and it is one of the objects of this invention to provide improved suction nozzles or cups for the purpose of separating and feeding the sheet to the platen. Another object is to provide a construction in which the sheet may be conveyed directly to the platen within the limits of movements of the stop gages.

With the above and other objects in view, the invention is embodied in an automatic sheet feeding mechanism arranged and constructed as hereinafter set forth and as illustrated in accompanying drawings in which

Fig. 1 is a side view of a platen press equipped with a sheet feeding mechanism embodying the invention, with parts omitted and broken away.

Fig. 2 is an enlarged view of parts of the feeder viewing it from the opposite side and with parts broken away.

Fig. 3 is a detail view showing the feeding suction cups in the position of seizing a sheet.

Fig. 4 is a diagrammatic view looking in the direction of arrow 4 in Figure 1 showing the arrangement of the suction cups for separating and for feeding a sheet.

Fig. 5 is an elevation of a feeding suction cup.

Fig. 6 is a sectional view on line 6—6 of Figure 5.

Fig. 7 is a similar view on line 7—7 of Figure 5.

Figs. 8, 9, 10 and 11 are detail views of the separating suction cup.

Figs. 12, 13 and 14 are views of the valve which controls the suction.

The present feeder is particularly designed for use on a Chandler & Price job printing press, without, however, being expressly limited thereto. These presses are so well known in the art that only the briefest description is required in order to understand

the invention. Referring to Figure 1 the press is identified by the frame 1, the rocking platen 2 and the form member 3. 4 is the driving pinion which meshes with a gear 5 on a shaft 6. The form member 3 is operated in the usual manner by connecting rods 7, one on each side of the press. The connecting rod is pivoted at 8 to the gear 5.

The feeder according to this invention comprises means for supporting the paper to be fed, a sheet separating mechanism, a sheet conveying or feeding mechanism, a valve for controlling the suction and incidental operating and supporting parts.

The paper 10 is supported on an inclined paper table 11 resting upon suitable brackets 12 and 13. The paper table is provided with means for properly positioning the paper. These means are not shown as they form no part of this invention.

The separating mechanism consists of one or more pneumatic separators or suction cups which are operated to pick up the top sheet of the pile and raise it to position when it may be seized by the feeding suction cups.

Each separate or suction cup consists of a bracket 14, Figures 8—11, adjustably secured as by a screw 15 to a square shaft 16. The bracket is formed with arcuate tracks or grooves 17, 17 and on one side a portion of the bracket is cut away as shown in Figure 9 to form a stop 18. The suction cup 19 is carried in a nozzle body 20 having arcuate rails 21, 21, one on each side, which slide in the aforesaid grooves 17. A tube 22 is secured to the body and communicates with the suction cup 19.

The body further carries a roller 23 and a pin 24. A spring 25 is interposed between the bracket and the body and tends to pull the latter from the position shown in full lines in Figure 9 to the position shown in dotted lines when the pin 24 abuts the stop 18. The shaft 16 is carried by two separator arms 26, 27 pivoted at 28, 28 near the lower edge of the paper table. To the one arm 27, Fig. 2, there is secured a depending lever 29 carrying a roller 30 which rests against a lifter cam 31 fast on a bell crank 32 pivoted on a bracket 34. The bell crank has a roller 35

which runs on a cam 36 on the shaft 6, see Figure 2. Flexible tubing 39 supplies suction to the cup 19.

As seen in Figure 4, there are three separating nozzles 19 carried by the shaft 16. Therefore, because of the weight of the nozzles and the shaft 16, the nozzles will rest by gravity on the paper and thus the roller 30 is held against the lifting cam 31. The parts are so arranged that the leftward movement of cam 31 is wide enough or far enough to the left in Figure 2, that said cam will never prevent the separating nozzles from resting on the paper by gravity. On the other hand, when the lifting cam 31 moves to the right, it will lift the nozzles 19 to a definite upper position away from the paper irrespective of the height of the pile.

After the top sheet has been separated from the paper and the forward portion of the sheet lifted as indicated in Figure 1, the separated sheet is seized by the feeding nozzles and conveyed to the platen to be placed there in printing position against the gages.

Each feeding nozzle, Figs. 5, 6 and 7, consists of a suction cup 40 carried by a nozzle member 41 pivoted to a nozzle body 42. The latter is carried at the bottom of a nozzle arm 43 secured to a shaft 44.

The nozzle arm 43 is in the form of a tube, closed at the top and at the bottom. Flexible tubes 45 and 46 communicate with the tube arm 43. The tube arm 46 leads to the nozzle member 41 and suction cup 40. The tube 45 leads to a common tube or pipe 47, Figure 4, from which latter a flexible tube 48 leads to the valve 50, Figure 1.

The suction cup 40 and nozzle member 41 are adapted to be moved with relation to the nozzle body 42 so as to direct the feeding angle or position of the paper while it is being conveyed to the platen and placed in final position against the gages. For this purpose there is provided a nozzle direction guide 51 pivoted at 52 to the nozzle member 41. The guide is slidably mounted on a rod 53 by means of a slot 54 and as it slides on the rod, the guide is guided in a slotted bracket 56 fast on the nozzle arm 43, Figures 5 and 6. A spring 55 is interposed between the bracket 56 and the guide 51.

The spring pulls the guide 51 upwards against the rod 53 as seen in Figure 2 and steadies the directive movement of the guide as well as to keep the nozzle member 41 up against a stop 57 on nozzle bracket 42. The shaft 44, rod 53 and pipe connection 46 are all mounted in two swinging arms 60 and 61, see Figure 4, which are fast on a shaft 62 which passes beneath the paper table 11. The shaft 62 is oscillated to swing the arms by a mechanism which is shown in Figure 1 and which consists of an arm 63 fast on the shaft at one end while the other end is de-

tachably connected at 64 to a link 65. The lower end of the latter is adjustably pivoted at 66 to a cam plate 67 pivoted to the frame at 68. The cam plate is formed with a slotted cam 69 in which moves the stud 8 of the connecting rod 7.

It follows, that as the press operates the stud 8 will swing the cam 69 and cam plate 67 on the pivot 68 and in turn actuate link 65 and arm 63 to rock the shaft 62 and swing the arms 60—61 from a pick up position as shown in Figure 1 to a sheet delivery position shown in Figure 2.

The detachable connection at 64 is for the purpose of being able to disconnect the arm 63 from link 65 when it is desired to swing the arm 60—61 in over the paper for purpose of adjustments, making ready and the like.

From the foregoing description it will be noted that the paper separating nozzles 19 are mounted between the two lifting arms 26 and 27, and that the actuating mechanism therefor is conveniently located on the one side of the feeder as shown in Figure 2. The feeder nozzles 40 are mounted between the two swinging arms 60 and 61 with the actuating means located on the opposite side of the feeder as shown in Figure 1. This is recited merely for purposes of orientation. The parts may be rearranged in any suitable manner.

The mechanism for operating the feeder nozzles from the pick up position in Figure 1 to the delivery position in Figure 2 is shown in the latter figure as follows. To the nozzle shaft 44 there is secured an arm 65 which is pivotally connected to a link 66. The latter is in turn pivoted to a second link 67 which is pivoted at 68 to the arm 60. At the connecting point 69 between the links 66 and 67 there is mounted a guide roller 70. A spring 71 is interposed between the small arm 65 and the large arm 60. The spring pulls the system of levers 65—66—67 in a downward and inward direction and keeps the guide roller 70 on its guiding cam 72. The latter is suitably pivoted on the table frame 11 at 73 and has a slot 74 which fits over a fixed pin 75.

The guide cam 72 hangs by gravity against a lifting roller 76 carried by an arm 77 on a stud 78. Secured to the latter and depending therefrom is another arm 79 carrying a cam roller 80 which runs on an actuating cam 82.

The parts are so arranged that as the arms 60—61 are swung in over the platen (the guide cam 72 is in its lowermost relatively fixed position hanging on the pin 75 irrespective of the throw of the roller 76) the guide roller 70 runs on the cam 72 and thereby guides and controls the movement of the link 66 and the swing of the arm 65 which in turn oscillates the nozzle shaft 44 whereby to guide the feed nozzles in a path substantially

as shown by the dotted line 85. At the same time, due to the changing relation between the rod 53 and the nozzle guide 51, the nozzles 40 are moved downwardly so as to convey the paper practically parallel to the platen and into printing position against the gages 81. In actual practise the feed nozzles meet the platen at about the middle thereof. Adjustment of the throw of the feed nozzles is made by adjusting the link 65 angularly with relation to the nozzle shaft 44.

The reverse movement takes place when the arms 60-61 are swung in over the paper. As the nozzle guide roller 70 runs up on the guide cam 72, the nozzles are lifted and are brought into final pick up position when the roller comes to rest on the cam portion 83, Figure 2. During the reverse movement however, the guiding cam 72 is lifted and lowered through the instrumentality of the cam 82, roller 80, arms 79 and 77 and roller 76, the latter acting directly against the guiding cam. The lifting of the cam 72 is for the purpose of causing the feed nozzles to clear the upper edge of the platen as the latter moves down into printing position. In some Gordon presses it may not be necessary to do this. In such cases the guiding cam 72 may perhaps be stationary.

In order to pneumatically separate a sheet, pick it up and carry to the platen, suction is applied to the nozzles at the proper times and in synchronism with the operations of the feeder. It is obvious from what has been described that first suction is applied to the separating nozzles which must grip the top sheet and hold it until seized by the feeder nozzles to which the suction is then shifted.

At this time suction is cut off from the separator nozzles. Then, after the sheet has been conveyed to the platen, suction is cut off from the feeder nozzles and shifted back to the separator nozzles and so on. The control of the suction is embodied in a suction valve 50 consisting of two valve members 90 and 91. The member 90 is fast on the cam plate 67, Figure 12. The other member 91 is pivoted on a common stud 92. The member 90 has three parts 93, 94 and 95. The other member 91 has two parts 96 and 97. The parts are all provided with lateral openings 98. There are three hose connections leading from the valve to the feeder. Connection 99 leads from the pump (not shown) to "pump" port 94. Hose 48 leads from the "feeder" port to the feeder nozzles 40 through the connections described above. Still another hose 100 leads from the "separator" port to the separator nozzles 19, see Figure 4, there being preferably a fixed manifold tubular connection 101 between the hose 100 and the nozzles 19.

The movable valve member 91 is connected by a link 102, Figure 1, to a valve cam 103 which has a slotted cam 104 substantially similar to the cam 69 but provided with an

off set at 105. The valve cam is pivoted at 106 on the cam plate 67. The stud 8 on the connecting rod 7 operates the valve cam 103 as well as the general operating cam 69.

It follows therefore that when the two cams 69 and 104 coincide, the valve 50 merely moves with the cam plate 67, but that when the stud 8 passes the off set cam portion 105, the valve cam is moved relative to the cam 69 and the movable cam member 91 is moved on the stud 92 to shift the parts.

The operation is as follows: Let us assume that the parts are in the position shown in Figure 1. At this time the impression is on, the top sheet will have been separated from the pile and lifted, consequently it is held by the separator nozzles.

The line of suction is therefore from the pump through hose 99 to valve ports 94 and 97, hose 100, manifold 101 to nozzle tubes 39 to separator nozzles 19. At the same time it will be seen from Figure 14 that the feeder nozzles 40 communicate with the atmosphere via valve ports 96 and 93. It will further be noted from Figure 4, that at this time the separator nozzles 19 are at a slightly higher position than the feeder nozzles 40 so as to bring the sheet close up under the latter.

Immediately thereafter, as the press moves, the stud 8 engages the valve cam 103 and gives a quick movement thereto and through the link 102, the movable valve member is given a quick snappy movement whereby the ports are shifted. This brings the feeder port 96 into register with the pump port 94, while the separator port 97 registers with the atmosphere through the port 95. Consequently suction is applied to the feeder nozzles 40 which seize the sheet and convey it to the platen. At the end of the feeding stroke 105 the valve is again shifted to release the suction in the feeder nozzles 40 and apply it at the separator nozzles 19 to separate the next sheet.

There is a decided advantage in the valve construction herein disclosed. Inasmuch as the valve itself moves with the press and feeder, perfect timing is obtained with a minimum of parts and irrespective of the adjustment of the stroke of the feeder nozzles.

I claim:

1. An automatic feeder for platen presses comprising suction nozzles for separating the top sheet from a pile of sheets, other suction nozzles for seizing the separated sheet from the first named suction nozzles and means for operating the said other suction nozzles to convey the separated sheet to the platen.

2. In an automatic feeder for platen presses the combination of conveying suction nozzles, means for operating the same from a paper pick up position to a paper delivery position on the platen of the press, paper separating suction nozzles and means for operating the latter to separate the top sheet from a pile of

- paper and move it to the said conveying suction nozzles when the latter are in their paper pick up position.
3. In an automatic feeder for platen presses, the combination of separating suction nozzles for separating the top sheet from a pile of sheets, means for operating said separating nozzles to move the separated sheet to a predetermined relatively fixed position, paper feeding suction nozzles and means for operating the latter to seize the separated sheet of paper from the separating nozzles when the latter are in the said predetermined position and for feeding the separated sheet to the platen of the press.
4. In an automatic feeder for platen presses, the combination of paper separating suction nozzles, means for operating said nozzles into separating contact with the top sheet of a pile of paper and away therefrom to a predetermined fixed position, means for applying suction to said separating nozzles for separating the said top sheet from the pile, paper feeding suction nozzles, means for operating the same from a pick up position coinciding with said predetermined position and to a delivery position on the platen and means for automatically cutting off the suction to said separating nozzles and apply it to the said feeding nozzles when both of said nozzles have reached said predetermined position and for automatically cutting off the suction from the feeding nozzles and apply it to said separating nozzles when the feeding nozzles have reached the said delivery position.
5. The combination with a platen printing press including a platen and stop gages thereon for positioning a sheet to be printed, of paper supporting means, pneumatic paper separating means, means for operating the latter to separate a sheet of paper, pneumatic paper feeding means and means for operating the latter to convey the separated sheet of paper from said separating means direct to the platen into printing position thereon in accord with the position of the stop gages.
6. The combination with a platen printing press including a platen and stop gages thereon for positioning a sheet to be printed, of paper supporting means, pneumatic paper separating means, means for operating the latter to separate a sheet of paper, pneumatic paper feeding means and means for operating the latter to convey the separated sheet of paper from said separating means direct to the platen into printing position thereon in contact with the stop gages and means for adjusting the movement of the said feeding means to accord with the position of the stop gages.
7. The combination with a platen printing press, of an automatic feeder therefor comprising paper separating means and paper feeding means, mechanism for applying suc-
- tion to both of said means for separating and feeding a sheet of paper and a valve for controlling the said application of suction to accord with the movements of said separating and feeding means and with the movements of the press.
8. An automatic feeder for platen presses comprising pneumatic paper feeding means, a cam for operating the same, means for applying suction to said feeding means, a valve mounted on said cam for controlling the suction and means on said cam for operating the said valve.
9. An automatic feeder for platen presses comprising paper supporting means, a pair of upright swinging arms, paper feeding means carried between said arms, members for operating said paper feeding means mounted on one of said arms, a cam for guiding said members to cause them to operate said feeding means in a predetermined path and means for operating the said arms.
10. An automatic feeder for platen presses comprising paper supporting means, a pair of swinging arms mounted thereon, paper feeding suction nozzles carried between said arms, a plurality of interconnected levers for operating said paper feeding suction nozzles, a cam for guiding said levers to cause them to operate said nozzles in a predetermined path, means for operating the said arms and means for changing the position of the said nozzles while they move in the said predetermined path.
11. An automatic feeder for platen presses comprising a pair of upright swinging arms, a shaft and a rod mounted therebetween in parallel relation, paper feeding suction nozzles carried by said shaft and depending therefrom, means adjacent said arms for guiding the operations of the said nozzles and means extending from the latter and slidably engaging the said rod for changing the position of the nozzles during their operation.

AMOS ACKLEY.
